US00D981409S

(12) **United States Design Patent** (10) **Patent No.:** **US D981,409 S**
Choi (45) **Date of Patent:** **** Mar. 21, 2023**

(54) **KEYBOARD**

(71) Applicant: **Logitech Europe S.A.**, Lausanne (CH)

(72) Inventor: **Wai Bun Choi**, Hsinchu (TW)

(73) Assignee: **Logitech Europe S.A.**, Lausanne (CH)

(**) Term: **15 Years**

(21) Appl. No.: **29/811,524**

(22) Filed: **Oct. 14, 2021**

Related U.S. Application Data

(62) Division of application No. 29/690,297, filed on May 7, 2019, now Pat. No. Des. 948,508.

(57) **CLAIM**

The ornamental design for a keyboard, as shown and described.

DESCRIPTION

FIG. 1 is a perspective view from the upper front, right side of the keyboard showing our new design;

FIG. 2 is a perspective view from the upper back, left side thereof;

FIG. 3 is top plan view thereof;

FIG. 4 is a front elevation view thereof;

FIG. 5 is a back elevation view thereof;

FIG. 6 is a left side elevation view thereof; and,

FIG. 7 is a right side elevation view thereof.

The broken lines depicting portions of the keyboard form no part of the claimed design.

1 Claim, 4 Drawing Sheets
